Primary Examiner—Ted Shooman*Assistant Examiner*—Adir Aronovich*Attorney, Agent, or Firm*—Salter & Michaelson[57] **CLAIM**

The ornamental design for a combination key tag and bottle opener, as shown and described.

DESCRIPTION

FIG. 1 is a perspective view of a combination key tag and bottle opener showing my new design;

FIG. 2 is a front side elevational view thereof;

FIG. 3 is a rear side elevational view thereof;

FIG. 4 is a top plan view thereof;

FIG. 5 is a bottom plan view thereof;

FIG. 6 is a left end view thereof; and,

FIG. 7 is a right end view thereof.

The broken lines shown in FIG. 1 are for illustrative purposes only and form no part of the claimed design.
